(57) **CLAIM**

The ornamental design for an aerosol dispenser for a deodorant product, as shown and described.

DESCRIPTION

FIG. 1 is a first perspective view of an embodiment of an aerosol dispenser for a deodorant product;

FIG. 2 is a second perspective view of the aerosol dispenser for the deodorant product of FIG. 1;

FIG. 3 is a front view of the aerosol dispenser for the deodorant product of FIG. 1;

FIG. 4 is a first side view of the aerosol dispenser for the deodorant product of FIG. 1;

FIG. 5 is a back view of the aerosol dispenser for the deodorant product of FIG. 1;

FIG. 6 is a second side view of the aerosol dispenser for the deodorant product of FIG. 1;

FIG. 7 is a top view of the aerosol dispenser for the deodorant product of FIG. 1; and,

FIG. 8 is a bottom view of the aerosol dispenser for the deodorant product of FIG. 1.

The broken lines shown in the drawings are for environmental structure or boundaries that form no part of the design to be patented.
